UNITED STATES PATENT OFFICE

2,446,315

HOLDING MEANS FOR ICE-CREAM
CANS AND CARTONS

John P. Williams, Nashville, Tenn.

Application July 19, 1945, Serial No. 605,972

3 Claims. (Cl. 248—361)

1

This invention relates to ice cream cabinet accessories and appliances and has more specific reference to means for holding and clamping in place conventional cartons and cans, such as are used in delivering and dispensing ice cream at soda fountains and in similar places of business.

More specifically, the invention pertains to novel means to embrace the can or carton, said means being characterized by a part for coaction with the base of the carton, and an upstanding part which coacts with the upper, open end or mouth of said carton.

More specifically, and generically speaking, the invention is characterized by an adjustable clamp to embrace and hold the base of the carton, and an upright connected to and rising from said clamp, said upright being provided, at its upper end, with an adjustable wedge conveniently shaped to facilitate attachment thereto of the carton.

In carrying out the principles of the invention, I have produced a simple, strong, durable and readily insertable and removable carton and can holder which lends itself admirably well in achieving the ends sought.

Other objects, features, and advantages of the invention will become more readily apparent from the following description and the accompanying illustrative drawings.

In the drawings, wherein like numerals are employed to designate like parts throughout the views:

Figure 1 is a fragmentary sectional view showing an ice cream refrigerating, or equivalent, cabinet, showing a carton or can in the usual chamber therefor, and also showing the improved can holder, this as constructed in accordance with the principles of the present invention.

Figure 2 is a perspective view of one of the parts of the can-clamping means.

Figure 3 is a horizontal section through the lower or base portion of the holder.

Figure 4 is a view like Figure 1 showing the type of holder used when square cans and cartons are employed.

Figure 5 is a perspective view of the adjustable base-embracing and clamping means.

Figure 6 is a perspective view of the adjustable detent or wedge.

It is evident, having scanned the drawings, that two embodiments of the invention are shown. That is to say, the form of can-holding means cooperable with the cylindrical can or carton is shown in Figures 1 to 3; whereas the type employed in connection with rectangular cans and

cartons is shown in Figures 4 and 5. It is to be noted, however, that there are certain common and generic characteristics embodied in both styles or types, and the description and claims are worded accordingly.

Attention is first directed to Figures 1 to 3, inclusive. Here the cabinet is denoted by the numeral A, the carton or can is indicated at B, the receptacle or chamber is denoted at C, and the lid is at D. Whereas I have referred to both cartons and cans, it is believed that the expression "container" is broad enough to cover both, regardless of shape, material and size, and the description will proceed accordingly.

15 The means which surrounds the basal or bottom portion of the container is an annular band, this denoted by the numeral 8 in Figure 3. The free ends of the band are overlapped, one end carrying a bolt and nut 9 and the other end being slotted for coaction with the bolt. This provides an adjustable sliding overlapping joint, as at 10. The stand or leg 11 is disposed at a diametrically opposite point. It comprises a short foot 12 formed integrally and bent laterally from the lower end of the leg. Just above this foot the leg is bolted, as at 13, to said band 8. The body portion of the leg is provided with a slot 14. The upper end of the leg is bifurcated, as indicated at 15, the furcations being denoted by 20 the numerals 16.

In practice, the furcations 16 extend above the top of the can to accommodate a bolt and nut 17 which serves to assemble and adjustably hold in place the detent 18. This is in the form of a wedge and is provided with a lateral extension 19 forming a finger grip. It is easy to shove the wedge down, bind the parts together and lock the can B in the holder, that is, the frame 8 at the bottom and the leg 11 associated therewith.

40 In connection with the modification shown in Figures 4 and 5, it is to be observed, of course, that so far as the leg is concerned, it is the same part as is identified by the numeral 11 in Figure 3. Consequently, the same reference numerals apply, inasmuch as like reference characters identify like parts throughout all views. The only difference here is the embracing means or clamp which serves to fit in square cabinets.

45 This means is denoted by the numeral 20, as a unit, and comprises a pair of companion, L-shaped members. The portions 21 and 22, constituting the so-called long limbs, are overlapped and slotted, the slots 23 being lined up to accommodate the assembling and adjusting bolt

24. The short limbs 25 and 26 provide jaws to partly embrace the can (not shown), this in an obvious manner.

Reference being further had to the adjustable base embracing and clamping means in Figure 5, this lends itself adaptable to cabinets having square compartments. Also, it lends itself highly useful in connection with square cans and cartons such as are most usually employed in connection with a correspondingly square compartment. I might mention, however, that this same structure in Figure 5 can also clamp and hold in place cylindrical cans. And, of course, cylindrical cans can be placed in cabinets with square compartments, obviously. I might also stress the fact that in the structure seen at the upper right in Figure 1, the shank of the screw or bolt is threaded through a screw-threaded opening in the wedge 18. Thus, it is possible to adjust the wedge in relation to the leg 11 to fit cardboard cartons on the one hand and no further adjustment is necessary after that, as long as the cartons are used. Then, the same means can be adjusted to fit cans and so long as cans are used it is not necessary to constantly change or readjust the wedge. In other words, this arrangement is easy to set for both metal cans and cardboard cartons.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

1. In a harness-type holder for ice cream cans and cartons of the class described, a vertically elongated flat metal strap constituting a leg, the lower end of said strap being bent at right angles to the longitudinal dimension of the body portion to provide a lateral foot for coaction with the

can or carton, as the case may be, the extreme upper end of said leg being bifurcated, a wedge adapted to occupy a position in alignment and approximate parallelism with the bifurcated end of the leg, a bolt and nut mounted on and carried by said wedge, said bolt being adjustably connected with said furcations, and adjustable can clamping means detachably fastened to the lower portion of the leg in a position for coaction and association with said foot.

2. The structure defined in claim 1, said can clamping means being in the form of an annular clamping band, said band being adapted to surround the lower portion of the associated can, said band having its free ends overlapped and adjustably connected together, the intermediate portion of the band being separably bolted to the exterior of the leg at a point just above the lateral foot.

3. The structure specified in claim 1, said can clamping means comprising a pair of L-shaped members, said members being slotted and adjustably connected together in overlapping relation, and a bolt and nut arrangement for clamping one of the L-shaped members to the leg just above the foot.

JOHN P. WILLIAMS.
